UNITED STATES PATENT OFFICE

2,587,829

TOOL CABINET AND WORKBENCH

Alexander P. Fox, University City, and August D. Reisert, St. Louis, Mo., assignors to Lincoln Engineering Company, St. Louis, Mo., a corporation of Missouri

Application December 31, 1948, Serial No. 68,574

4 Claims. (Cl. 312—237)

1

This invention relates to a tool cabinet and workbench, and with regard to certain more specific features, to metal apparatus of this class for use as a repairman's service station in garages and the like.

Among the several objects of the invention may be noted the provision of a combined tool cabinet and workbench providing a rigid working surface with a conveniently located openable and closable tool cabinet wherein vibrations caused by working on the bench are isolated from the cabinet; and the provision of a combination of the class described wherein the cover for the tool cabinet forms an effective advertising display surface whether open or closed. Other objects will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which one of various possible embodiments of the invention is illustrated,

Fig. 1 is a front elevation of the combination showing the tool cabinet thereof in open position;

Fig. 2 is a plan view of Fig. 1;

Fig. 3 is a right-side view of Figs. 1 and 2;

Fig. 4 is a fragmentary isometric view illustrating a closed condition of the tool cabinet;

Fig. 5 is a fragmentary vertical section taken on line 5—5 of Fig. 1, showing a wash container in a retracted storage position;

Fig. 6 is a fragmentary view similar to Fig. 5 but showing the wash container in extended position;

Fig. 7 is an isometric view of said wash container in withdrawn position and illustrating a cooperative drain basket accessory;

Fig. 8 is a detail exploded view of a slide assembly;

Fig. 9 is a detail section of parts of said slide assembly when telescoped together;

Fig. 10 is an enlarged detail section taken on line 10—10 of Fig. 1; and,

Fig. 11 is a detail section taken on line 11—11 of Fig. 4.

Similar reference characters indicate corresponding parts throughout the several views of the drawings.

The present invention is directed primarily to equipment for garages and the like. In establish-

2

ments of this class, it is desirable to have a mechanic who does a particular type of work (for example, electrical work, brake work, body work, etc.) at a fixed station incorporating a workbench, a tool cabinet for his specialized tools, and usually a wash container for washing parts worked upon. Such stations, for best customer appeal, should be compact and modern in appearance, providing the essentials for a mechanic working at the station and displaying prominently the type of service rendered at his station. It is preferable that such a station form a sufficient storage space for the usual tools employed by the mechanic.

15 Referring more particularly to the drawings, numeral 1 in general indicates a workbench component of the invention, numeral 3 a tool cabinet component, and numeral 5 a wash container component.

20 The workbench component is constituted by a top 7 providing a flat working space, supported upon end panels 9. The panels are stiffened at their forward edges by providing each with a U-turn 11. This directs their margins 13 inward.

25 The margins 13 are turned in on arcs of substantial radii, so that a semi-tubular type of support is afforded.

The inner edges of the margins 13 are formed as angled stiffening flanges 15. The other margins of the panels 9 are angled as shown at 17, being provided with inturned stiffening flanges 19 to form supporting channels. Supported upon angle irons 21 on the end panels 9 is a bottom shelf 23. In view of the above construction, the top 7 considerably overhangs the shelf 23 in a forward direction. A flanged rear inset panel 25 closes in the back of the bench between the top 7 and the shelf 23, leaving open the back of the bench under the shelf. This provides for easy cleaning beneath the bench.

30 40 The forms of the margins of panels 9 at the front and rear provide for a rugged supporting construction for the bench top that at the same time has a simple and modern appearance.

Substantially all of the bench parts, as well as the parts to be described, are formed of metal. The chief exception is a non-metallic facing 27 which may be applied to the top 7, as required. The shelf 23 is for a portable tool cabinet if the mechanic employs his own.

50 55 Referring now to the tool cabinet section 3, it is constituted by hollow, shell-like end panels 29, joined by means of a bottom 31 and a back 33. These panels are rounded at their front upper corners. Elsewhere these end panels are spaced apart without an intermediate connection. The

back 33 is provided with suitable holes for accepting studs (as desired) to function as supports for tools. It is also provided with shelves 35 which extend into the hollow end panels 29. Bolted to the ends of the cabinet are vertical supporting legs 37 which are braced to the bottom 31 in a plane behind the bench section 1, as shown at 39. The bottom 31 of the cabinet is spaced above the top of the bench section 1 and the inner sides of the supports 37 are spaced outward from the ends of bench section 1, a rubber molding 41 being employed between the top 7 and the bottom 31. The cabinet extends rearward from the rear of the bench 1 and only a narrow forward portion of the bottom of the cabinet overlies the top of the bench (Figs. 2 and 3). The molding prevents articles on the bench from being lost over the back of the bench and under the tool cabinet. The sections 1 and 3 are bolted to the floor. From the above it will be clear that any vibrations of the bench section caused by working thereon will be isolated from the tool cabinet. This is a desirable feature where all parts are made of metal, and reduces noise and clatter from parts stored in the tool cabinet and from the display parts associated therewith and to be described below.

The tool cabinet is provided with a special closure comprising a hollow top cover 43 rearwardly hinged at 45 to the upper edge of the back 33. To the front edge of the top cover 43 is hinged a front cover 47, as shown at 49. The top cover is curved as shown at 51, to match (when closed) the curvature 53 of the top corners of the cabinet end shells 29. This serves two purposes: first, to bring the hinge 49 well down when the covers 43 and 47 are placed in closed position, as shown in Fig. 4; and second, to place the plane of the open front cover 47 well forward of the rear of the device when open (see Fig. 3). These are desirable features because the front cover 47 also serves the purpose of a display panel to advertise, for example, the services being rendered by the operator who works at the bench. Advertising spaces are outlined at numerals 55. The front cover 47 extends upward as shown at 51, to increase the display area.

In order properly to guide the lower edge of the cover 47, its lower corners are provided with pins 59 carrying rollers 61 operative in guide grooves 63 formed on the inner edges of the cabinet ends 29. These grooves, beyond their curves at the corners 53, are formed with upper-end, depressed detent cams 65, with which the rollers 61 cooperate when the covers are open, to hold the open position of cover parts shown in Figs. 1-3. Knobs 67 provide for manually actuating the covers to open and closed positions. Thus the tool cabinet when closed or open provides an effective display area. As above stated, working blows upon the bench are not transmitted to the tool cabinet, nor to the metal display panel, which might otherwise undesirably reverberate.

If desired, suitable electrical and/or air outlets may be located in the lower forward areas of the cabinet ends 29, the locations being indicated at numeral 69. The outlets have not been shown at these points, because their use and forms are optional.

Referring now to the wash container section 5, it comprises an L-shaped bracket 71, the lower end of which is supported upon the shelf 23 and the upper end upon one end panel 9. This shape of the bracket provides storage space beneath it. On its upper surface it carries a pair of angle

irons 13. Bolted to the inside of each iron is an inner channel 75 within which telescopes an intermediate slide 77. An outer slide channel 79 telescopes with the intermediate slide 77. Struck-out stops 81 limit the extent to which the members 75, 77, 79 may be extended by telescoping, as illustrated in Fig. 6. The slide channels 79 support a bracket 83 upon which is carried a liquid-tight solvent container 85, having a bottom drain plug 87. This container has located across the sides of its mouth spaced tubes 89. These intersect the front and back of the container and form guides for rods 91. These rods at their front ends carry a bracket 93 which supports a sloping captive drain tray 95, the latter having an inner flange 97 forming a limiting stop engaging the front of the container 85 when pulled open. As an accessory may be used a drain basket 99 having a pivoted bail 101 and a reticulated bottom 103. This basket is accepted in the container 85 between the guide tubes 89. When so accepted and the bail 101 is turned down, the drain pan 95 may be pushed over to form a closure for the container 85. The latter may then be pushed into the retracted position shown in Fig. 5. The parts may be pulled out to the Fig. 6 position, wherein the container 85 is just beyond the front edge of the bench, the tray being pulled out farther. Parts may then be washed in the container 85, with or without use of the drain basket 99, and then placed upon the extended drain pan 95 for drainage of excess solvent back into the container. Also, the container 85 may be pulled out while the pan 95 is left as an upper closure for it, in which event the drain tray may be used as a convenient place temporarily to lay small parts such as nuts, bolts, washers, etc. Or, the tray may be pulled forward beyond the bench top without pulling out the container. When not in use, the wash container assembly may be pushed into the retracted position shown in Fig. 5.

While the wash container assembly is shown as being mounted upon the bracket 71, it will be evident that it could be suspended from the bottom of the bench top 7.

In view of the above, it will be seen that we have provided a combination workbench and tool cabinet arrangement which is particularly useful for public work shops such as garages, filling stations, and the like, wherein neatness, quietness of activity, and a display effect are at a premium, whether or not the apparatus concerned is in or out of use. Moreover, the construction is strong but provides in work shop furniture a desirable modern appearance such as is ordinarily associated with less strong office furniture.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

We claim:

1. In combination, a workbench having a flat top providing a flat working space, a tool cabinet mounted on legs supporting it above a floor in position extending from end to end and at the rear of the workbench with the bottom of the cabinet spaced above the top of the workbench and with the cabinet-supporting legs spaced from the workbench, and a resilient molding in the

space between the top of the workbench and the bottom of the cabinet.

2. The combination set forth in claim 1 wherein in the cabinet has end panels joined by a bottom and a back and the cabinet-supporting legs are fixed to the end panels and are spaced outward from the ends of the workbench.

3. The combination set forth in claim 2, wherein in the cabinet extends rearward from the rear of the workbench and only a narrow forward portion of the bottom of the cabinet overlies the top of the workbench.

4. The combination set forth in claim 1 wherein in the cabinet has a display-forming front door which is mounted for upward and downward movement between a lower vertical closed position and a raised vertical open position.
